POWER GENERATING AND SUPERHEATING METHOD, AND APPARATUS THEREFOR

Will H. Rowand, Short Hills, N. J., assignor to The Babcock & Wilcox Company, Rockleigh, N. J., a corporation of New Jersey

Application October 8, 1951, Serial No. 250,268

9 Claims. (Cl. 122—479)

This invention relates to a method of vapor generation and superheating, and a vapor generating and superheating unit of the once-through type for carrying out the method.

More specifically, the invention relates to improvements in superheated steam generators of the once-through type in which the operating medium is forced under pressure into one end of an externally heated tubular passage or passages and is delivered from the outlet end or ends of the passage or passages as highly superheated vapor.

The invention also involves a method of operation of such a steam or vapor generator, the method including the limiting of the liquid to vapor transition zone to the convection section by the coordination of load, furnace firing rate and furnace temperature with the variable proportioning of furnace and convection section absorption of the total available heat in counter-acting relation to the tendency of the transition zone to move toward or from the furnace under the influence of load changes.

It is an object of the invention to provide a forced-flow tubular steam generator having a transition zone wherein the position at which the working fluid is completely converted from the liquid to the vapor state located in a portion of the heating space of such relatively low heat intensity that injury to the tubing of the transition zone will be minimized, even though such tubing may accumulate chemical deposits at the transition position, together with means responsive to characteristics of the working fluid to control the distribution of heat application between the radiant vaporizing and convection superheating surfaces in such a manner as to prevent substantial shifting of the transition position within the tubing of the transition zone, particularly under variable load or slagging furnace conditions.

The invention minimizes load variation shifting of the transition position in a forced-flow vapor generating and superheating unit having radiantly heated liquid containing tubes in the combustion chamber walls and serially connected convection heated tubes comprising the transition zone including the transition position located in a heating space receiving gases from the combustion chamber, by controlling the proportion of heat absorbed by the furnace tubes as compared with the heat delivered to the convection heated tubular heat absorbing surfaces.

More specifically, the invention provides, in a forced flow once-through vapor generator, for the regulation of the combustion chamber temperatures and control thereby of the radiant heat absorption by its walls, and control of the exit gas temperature from the combustion chamber, by introducing recirculated cooled heating gases to one or more selected positions in the furnace.

A further object of the invention is to provide apparatus whereby the selective regulation of recirculated gas introduction is controlled by means responsive to the

2

temperature of the partially superheated vapor and by means responsive to combustion chamber temperatures, while the supply of combustion media is controlled jointly from the flow and temperature of the delivered superheated vapor.

The pertinent vapor generating and superheating unit of this invention involves a section including one or more tubes into the inlet ends of which a vaporizable liquid is pumped at high pressure. Within this tube, or these tubes, the vaporization of the liquid is completed and the vapor is superheated. There is thus a transition zone within these tubes and it has been found that the variations involved in the temperatures of the gases heating such tubes cause corrosion of the tube metal because of chemical deposits from the vaporizable liquid.

Attempts have been made to remedy the above indicated difficulty, such attempts involving a re-routing of the tubes of the transition zone relative to that zone and the furnace zone from which the gases pass to the former. Such attempts have not been successful because they have limited the effective load range of the pertinent units and have thus seriously limited the commercial application of units of this type. They have also undesirably involved low feed water temperatures.

25 This invention involves the recirculation of furnace gases from a position downstream gas flow-wise of the transition section of an associated vapor superheater to a position near the gas exit of the furnace and/or to a position upstream gas flow-wise from the furnace burners, to reduce the total amount of heat absorption by the evaporating wall surface of the furnace to a point where feed water temperatures can be raised to desirably high values and to permit a wide load range on the unit while still keeping the transition zone in a position of such lowered gas temperature that the difficulties arising from chemical deposits and tube metal corrosion in the transition zone are minimized.

The invention increases the overall thermal efficiency of the pertinent type of vapor generating and superheating unit and makes it particularly applicable for operation at fluid pressures varying from 2000 p. s. i. to 5000 p. s. i.

40 The invention will be described with reference to the accompanying drawings in which the transition zone is disposed in a convection gas pass receiving gases from a furnace section, the walls of which include tubes in which the vaporizable liquid is heated for series flow therefrom to the transition zone, the heat absorption by the tubes of the furnace zone being increased when operating conditions would otherwise involve an undesirable effect on the location of the transition zone.

45 The transition zone is included in series connected return bend tubular sections extending transversely of gas flow in the convection section. Thus, the pertinent part 55 of the convection section involves long or continuous conduits into the inlet ends of which a vaporizable liquid is pumped at high pressures. Within these conduits the completion of the vaporization is accomplished and the vapor is superheated. From the outlets of these tubes 60 the superheated vapor passes to a bank of tubes for further superheating in a high temperature superheating zone, these tubes being disposed transversely of the furnace gases flowing from the furnace section to the transition zone.

65 The burners for the furnace zone are disposed between two locations at either or both of which recirculated gases, from a position in the gas stream downstream of the transition zone, are controllably introduced to properly vary and control the heat absorption of the wall tubes of the furnace zone and control the gas temperature at the furnace outlet.

In the drawings:

Fig. 1 is a diagrammatic view of a control system for the illustrative vapor generating unit;

Fig. 2 is a diagram illustrating the forced flow of fluid through the various components of the unit; and

Fig. 3 is an enlarged vertical section through the illustrative vapor generating and superheating unit.

If a once-through boiler is considered as consisting of a single length of tubing with water introduced at one end and heat applied along the tube so that superheated steam is delivered from the other end, we have a situation in which at some localized position the final and complete vaporization of the fluid takes place. This is a place of initial dryness with 100% steam quality and is variously referred to as the conversion or transition position. Ahead of this position, i. e. from the position of water introduction up to the transition position, the water is being progressively heated up to saturation temperature and then progressively vaporized up to the transition position. From the transition position to the steam outlet or delivery point, in so far as the tubing is subjected to heating gases of sufficient temperature, there is an increase in heat content of the steam with an increase of temperature or degree of superheat.

If such a boiler is operated with a variable rate of feed water introduction, that is, if the feed rate is raised or lowered, with a corresponding modification of heat input in order to obtain proper thermal efficiency, then the position of the conversion or transition position will shift, particularly in those installations where a portion of the vaporization heat input is accomplished by furnace wall tubes. The transition position will shift toward the feed inlet end of the tube with reductions in feed flow and toward the superheater outlet end with increases in feed.

The transition position and the length of tubing or zone through which this position moves with varying loads, has been subject to the deposition of chemical salts from the water as the result of evaporation to dryness. When this transition point and the zone is placed in a high temperature position, for example, in the furnace, this salt deposit so reduces the heat transfer that the tubing becomes overheated and fails. It has been proposed to take the transition zone out of the high temperature heat absorbing position by placing it back in the convection pass so that even though internal accumulation of salts did occur the heat transfer would be so low that overheating would not occur during the operating period. The salts would then be removed by washing or otherwise.

The particular fault of such an arrangement is that inasmuch as the conversion position is not fixed within the tube but shifts through a considerable length of tubing when operated over variable loads, it involves a considerable length of tubing which must be frequently cleaned and given better protection against failure by overheating and corrosion by the use of the proper alloy steel.

This invention minimizes the shifting of the transition zone, thereby reducing installation costs by minimizing the amount of highly expensive metals which would otherwise be required in the superheating zone.

Further, the invention involves gas recirculation to effect a modification of water cooled furnace heat absorption, for the purpose of control of the ratio of heat absorbed in the furnace to the heat absorbed in the superheating and convection pass over a wide load range, to the end that the conversion position may be maintained without substantial shifting regardless of load.

Where water-cooled wall furnaces are used in once-through forced circulation boilers, and the volumes of the furnaces are sized so as to insure a gas temperature leaving the furnaces which will be sufficiently low to avoid slagging difficulties, particularly in the case of pulverized coal firing, the amount of heat absorbed by the furnace walls is such a great proportion of the total necessary to evaporate the water and superheat the steam, that there is little evaporation to be accomplished in a transition

zone if it is moved into a relatively cool gas pass. If the amount of heating surface located in the gas pass is of considerable extent the reduction of load might not shift the transition position back into the tubes of the furnace lining, but this would not be feasible if an advantageous range of load variation is to be accomplished.

The invention has two phases—both of which are related to gas recirculation. The one phase is that involving gas recirculation to affect furnace heat absorption to the end that the transition position shifting is minimized. This is by the introduction of the recirculated gas to the bottom of the furnace. The second phase involves the utilization of gas recirculation for the high load range, introducing it into the upper portion of the furnace as close to the furnace gas outlet and convection pass inlet as possible when considering the matter of gas mixing, so that the gas temperature at the entrance of the convection pass may be minimized irrespective of the rate of heat liberation by fuel burning.

Fig. 1 of the accompanying drawings involves a vertically extended furnace the boundary surfaces of which include wall tubes for heating a vaporizable fluid pumped into the inlets of the wall tube system at a high pressure.

This vertically elongated furnace 10 provides a radiation zone or furnace zone in which the vaporizable fluid is heated. The vaporizable fluid is pumped into the economizer inlet header 12 for flow through a liquid heating zone E, serially connected return bend tubes constituting the banks of tubes 14 and 16 of this zone. These tubes lead to an outlet header 18 from which the fluid flows to appropriate inlet headers such as those illustrated at 20 and 22 at the bottom of the furnace zone.

The high temperature vaporizable liquid flows from the lower headers 20 and 22 through the wall tubes of the furnace and to such tubular connections as those indicated at 24 and 26, leading from headers 28 and 30 disposed at the top of the furnace zone and connected to the outlet ends of the furnace wall tubes. The fluid flows through these connections 24 and 26 to the components

32, 33 and 34 (Fig. 2) of a U-shaped lower header for the walls of the gas pass which may be considered as providing a secondary convection fluid heating zone. This lower header is indicated in its entirety by the numeral 36. From the component 34 of this inlet header for the gas pass walls, the fluid flows through the wall tubes 38 to a superposed component 40 of a similarly U-shaped oppositely arranged upper gas pass header indicated in its entirety at 42 (Fig. 2). Similarly, fluid flows from the component 32 of the lower header 36 through the side wall tubes 44 to a component 46 of the upper gas pass header.

From the rear wall component 33 of the lower header 36 the fluid flows upwardly through wall tubes 48, the upper parts of which have roof tube sections 50 directly leading to the component 52 of the upper gas pass header.

From this header, the fluid flows to the inlet header 58 of the transition section. This transition section is formed by superposed banks 60—63 of serially connected return bend tubes, leading to outlet header 66 from which the superheated vapor flows through the conduit 68 to an attemperator 70 and thence to the inlet header 72 of the superheater S. Here, the vapor is further superheated to higher temperatures within continuous conduits consisting of serially connected banks 74 (Figs. 1 and 3) of return bend tubes, the outlets of these tubes being connected to the outlet header 78 from which the highly superheated and high pressure vapor passes to a point of use.

For a clearer understanding of the flow circuits of the illustrated unit, Fig. 2 diagrammatically discloses the economizer E into the tubes of which liquid is forced at high pressure by the pump 80. From the economizer outlet header 18, fluid flow takes place through the connectors such as 82 and 84 to the header section 22 and an adjacent header section 20 along the same furnace wall

65 of the furnace subhopper 88.

70

75

76

77

78

From the small header or header section 22, the fluid passes upwardly through the furnace wall tubes extending along the right hand side of the combustion chamber 10, as it is shown in Fig. 1. This wall may be also referred to as the rear wall of the furnace. These tubes have their lower parts 90 extending along the wall of the sub-hopper 88 and succeeding parts 92 upwardly inclined toward the right and extending along the right hand wall 94 of the hopper 96, thence the tube parts 98 extend along the division wall between the gas pass 100 and the combustion chamber. Above these parts the tubes have other parts 102 associated with appropriate heat resisting material 104 to form the wall of a gas pass across the rear side of the furnace arch 106, the upper part of which forms the lower wall 113 of the furnace or combustion chamber gas outlet in which the superheater S is located. The upper wall of the arch is defined by the tube parts 110 (Fig. 3) together with associated and suitable heat resisting material 112, and the lower part of this arch is defined by the tube parts 114 and associated heat resisting material 116. At the rear of the superheater S the parts 118 and 120 of the vapor generating tubes form a screen through which the gases pass to a gas turning space 122 at the top of the transition section and the gas pass 100. The pertinent vapor generating tubes extend as roof tubes 124 and 124' associated with appropriate heat resisting material 126 to form the roof of the illustrative unit. As a screen for the superheater S, some of the fluid heating tubes continue from the parts 114 directly vertically past the nose of the arch 106. From this screen, the tubes continue to the outlet header 28.

Referring back to Fig. 2, the lower headers for the furnace or radiation section R may be formed as small units such as 130—134 leading to the right of the inlet header section 22, or the headers may be diaphragmed to provide such small header sections. Similarly, successive small header sections 136 and 138 are arranged at the left of the inlet connection 82. The header arrangement at the top of the furnace section includes similar small header sections 141—147.

The fluid flow from the economizer E of Fig. 2 through the header 18 and the connector 84 continues through the header section 22 and thence through connected wall tubes 23 upwardly to the header section 145. It continues from this header section through one or more downcomers 150 to the next lower header section 130. From the latter, the flow is upwardly through connected wall tubes 23 to the header section 146. From this header the flow continues through succeeding wall tubes 25 and downcomers to the upper header section 28 from which the fluid flows through lines 24 and 27 to the header components 32 and 33 of the secondary convection fluid heating zone G.

Similar flow continues from the economizer outlet header 18 through the connector 82 and header section 86. From this header section the flow takes place through connected wall tubes 29 discharging fluid to the upper header section 144. From this header the fluid flows downwardly through the downcomer 150 to the succeeding lower header section 136, the flow continuing in this manner around the walls of the furnace section to the upper header section 30. From this header section the fluid flows through a connector 26 to the component 34 of the lower header of the secondary convection fluid heating zone involving the walls of the gas pass 100.

Flow continues upwardly through the wall tubes of the secondary convection fluid heating zone or the gas pass wall section to the upper U-shaped header 42 for the gas pass. From the components of this header, fluid flows through the lines or conduits 152—154 to the inlet header 58 of the transition section T. The flow continues through the serially connected tubes of this section to the outlet header 66, the conduit 68, the attemperator 70 and the inlet header 72 of the superheater S. From

the outlet header 78 the superheated vapor flows to a point of use.

Referring further to the diagrammatic disclosure of Fig. 2, it is to be understood that the disclosure of the radiation zone structure at R indicates the entry of fluid into two adjacent header sections 22 and 86 in the mid-part of the right hand or rear wall (Fig. 1) of the combustion chamber. The succeeding header sections such as 145, 146, 147, 130—132 to the right of the line 84 represent the upper and lower header sections for one-half of the rear wall of the combustion chamber, then the corresponding header sections for one side wall, the last few upper and lower header sections at the right hand part of Fig. 2 indicating the upper and lower header sections of one-half of the front wall of the combustion chamber. Similarly, the successive upper and lower header sections to the left of the line 82 represent first the remainder of the header sections for the rear wall, then the header sections for the other side wall, and beyond that the corresponding header sections for the remainder of the front wall of the combustion chamber. In other words, the component parts of Fig. 2 represent the walls of the combustion chamber folded into a single plane which might be considered the plane of the rear wall of the combustion chamber.

The invention involves the maintenance of the zone of transition from a liquid-vapor mixture to completely vaporized condition at some position along the once-through tubes extending from the inlet header 58 to the outlet header 66 of the transition section, and a temperature control point such as T' is so selected that it is at a minimum distance above or beyond the inlet header 58 only sufficiently that under all load variations (and attendant factor variations), the transition zone is always 35 above the lower header 58 of the transition section.

To maintain the transition zone within the stated limitations, flue gas recirculation, either to the hopper throat 170 (through a plurality of ports distributed along the throat) or through a plurality of wall openings such as 172 connecting with a transverse duct 178, or both, in controlled quantities, is effected by the invention.

Flue gases are extracted from the gas turning space 180 at the bottom of the gas pass 100 through an upright duct 182. The gas is forced by a fan 184 through a horizontal duct 186, to a junction box 188 and then through a duct extension 190 in which a control damper 192 is positioned. From the junction box, controlled flow of recirculated gas also takes place through upright duct 194 and then through transverse duct 178. Flow through the duct 194 is controlled by a damper 196. Flow from the transverse duct 178 continues into the furnace through ports 172.

For automatic control of the illustrative system pressure responsive control element P is connected to the superheated steam line 200 leading from the outlet header 78 of the high temperature superheater. From this control element, such as a Bourdon tube, pressure impulses are communicated through a pneumatic pilot valve 203 (such as shown in U. S. patent to Johnson 2,054,464), 55 a loading line 202, an averaging relay 210 (such as shown by U. S. Patent 2,098,913, device 13 of that patent), line 209, and motor controller 211 for an electric motor for driving the pump 80 for forcing water into the inlet header 12 of the economizer. The water delivery of this pump is also controllable from load variations, the load impulses being transmitted as representative of steam flow-water flow-ratio by the pilot valve 205 and the line 206 from an orifice device F (or steam flow controller) having tubular connections to opposite sides of the orifice 208, and measuring steam flow. The impulses from steam flow controller F are modified by impulses from water flow controller W connected by lines 213 and 215 to opposite sides of the orifice 217. For these combined impulses the devices F and W are indicated as interconnected at 221. The flow

meters or controllers F and W as well as the recirculated gas flow controller 252 may be of the type shown by Patent 1,064,748. Fig. 1 of Albright 1,962,676 also shows how such a steam flow meter and water flow meter may be interconnected by linkage to position a pilot valve (such as 205) in accord with the relations between the two fluid flow rates. Further, Fig. 4 of Birchler 2,526,843 shows another way of inter-relating steam flow and water flow where each of two meters establishes a fluid loading pressure and then the two loading pressures enter a ratio gauge setting up a resultant fluid pressure in pipe leading to averaging relay 15A. The steam flow, or load line 206, joins the pressure line 202, at the averaging relay 210 by which combined pressure impulses and steam flow-water flow-ratio impulses are transmitted to the motor controller 211 for the variable speed pump motor to control the operation of the water pump 80 in desired or controlled ratios.

The operator 211 may involve a servo-motor such as that shown at 40 in U. S. Patent 2,298,257 operating the movable member of a combined switch and rheostat. The relay 210 is capable of being so adjusted that either one of the pressure or load impulses may have a predominating effect upon the fluid pressure in the line 209, and hence, upon the operation of the pump 80.

The steam flow controller, or orifice device F measures steam flow, or boiler load, and, associated with one or more pilot valves, such as 201, effects load variations in the loading lines 212, 216, and 226.

Assuming that the fan 184 is operated at a constant speed, the dampers 192 and 196 are so operated as to cause a maximum flow of recirculated flue gas into the hopper throat through the duct 190 at a low load. Under such conditions the minimum flow takes place through the upright duct 194 and the connected upper recirculated gas openings or ports 172, the dampers being automatically controlled to accomplish this result. This automatic control involves a temperature responsive element K, responsive to gas temperatures at the outlet of the furnace or, gas inlet of the high temperature superheater, the temperature indications of this element being transmitted through line 191 to gas temperature controller 193 and then transmitted as pressure loading impulses through a pilot valve 197. These impulses are then transmitted from that valve as corresponding loading variations through a line 212' to totalizing relay 195, and then through selector valve 199 and line 207 to a valve operator 214 for the damper 196. These control impulses are modified by steam flow, or load impulses transmitted from the control device F through pilot valve 201, line 212, and the line 216 to relay 195. The relative effects of the gas temperature impulses and the load impulses may be desirably regulated for their effect upon the damper 196 and the gas flow through the upper ports 172 so that one or the other of the impulses may have a predominating effect.

The flow of recirculated flue gas through the duct 190 to the hopper throat 170 is controlled by intermediate steam temperature controller T" responsive to superheat temperatures (at T') in one or more tubes beyond the transition position. From this element and its pilot valve 219, temperature indications are transmitted as corresponding loading variations or impulses through the line 220, the totalizing relay 221', line 223, selector valve 225, and line 227 to the damper operator 222 (similar to operator 214) for the damper 192. These temperature impulses, from intermediate steam temperature controller T", are controllably modified by a multiple chamber averaging (or totalizing) relay 221' (similar to relay 210), one of the fluid chambers of which is connected by the line 226 to the pilot valve 201 of the steam flow measuring device, or steam flow controller F. The relay 221' also receives modifying impulses representative of changes in the flow of recirculated gases through the duct 182. For this purpose, the recirculated gas flow

controller 252 is connected by the lines 254 and 256 to opposite sides of the orifice 258. Changes in the pertinent gas flow are measured by the controller 252 and translated into representative loading impulses by the associated pilot valve 260, and its associated connections. These impulses are then transmitted to relay 221' through line 262.

The control of the operation of the burners 230 for the combustion chamber is effected by control impulses transmitted to fuel and air control, or primary air damper drive 240 (which may involve one or more servo-motors such as shown in the Johnson Patent 2,536,184, January 2, 1951) in which the control impulses are selectively proportionately derived from the final steam temperature controller T³ connected to temperature responsive element 241 in the steam line 200, and the steam flow controller, or load measuring device F. Fig. 1 of the Wheaton Patent 2,155,986 shows a steam temperature controller, which is representative of the steam temperature controllers T" and T³.

The final steam temperature controller T³, connected to the temperature responsive element 241 by the line 270, controls the final temperature in the steam in the line 200, and through the associated pilot valve 272 transmits representative loading variations in the line 274 to the relay 276. The load impulses through the line 274 are controllably varied by this relay and are transmitted therefrom by the line 278 to one of the operative chambers of the totalizing relay 280.

The relay 280 also receives load impulses from the steam flow controller F, through the line 216. Thus, the loading impulses transmitted by the line 282 from the relay 280 to the selector valve 284 are the results of the combined effect of the load impulses in the lines 278 and 216 entering the relay 280.

The location of the transition position depends upon the amount of heat absorbed in the furnace wall generating tubes, and one effect of this invention is to controllably vary the amount of such heat absorption.

In an uncontrolled unit proportionate heat absorption by the furnace wall tubes varies with the load and tends to increase as the load drops. This would cause a tendency of the transition zone to move into the furnace. The range of movement of the transition zone is minimized by the controlled recirculation of flue gas into the furnace to control the heat absorption by the furnace wall tubes.

In general, the volume of recirculated gas increases as the boiler load decreases to maintain the transition position within the desired limits. The illustrative control system is effective to vary the amount of flue gas introduction into the furnace and the position of that introduction into the furnace from variables which include the fluid temperature at T'. This control point is on the superheated steam side of the transition zone.

The illustrative control system is effective to accomplish the desired results by producing a maximum introduction of recirculated gases at low load through the duct 190 into the hopper throat of the installation, the flow of recirculated flue gas at this position being reduced to zero as the load increases to a maximum flow. Reversely, the maximum of recirculated flue gas takes place through the upper ports 172 at full load and is reduced toward zero at low load.

When the unit is operating at maximum steam output recirculated gas will be introduced into the upper ports 172, thereby adding gas weight to the fresh products of combustion but diluting them so that the temperature leaving the furnace is below a predetermined maximum.

This introduction of recirculated gases to the upper portion of furnace will not effect a substantial reduction in the radiant absorption of the furnace walls, but on the other hand it does increase the gas weight flowing over the convection surfaces.

When the steam demand is reduced, the control effects

a reduction in feed delivery from pump 80 and a reduction of fuel and combustion air input. The reduction in heat release in the furnace will drop the furnace exit gas temperature, permitting a reduction in the recirculated gas added through ports 172.

As the radiant heat absorption in the furnace walls will drop only slightly with the reduced heat input and not proportionately with the reduced water flow, the position in the tubes at which the fluid is completely evaporated in transition section T will move downward toward the inlet header 58. This will result in a rise in the slight degree of vapor superheat determined by temperature responsive element T''.

When the temperature determined by T'' rises, it operates conjointly through 221 with a determination of the reduced steam output to effect an adjustment of damper 192 to regulate introduction of recirculated gas into the throat of the furnace.

Such introduction of recirculated gases into the bottom of the furnace will reduce the radiant absorption of heat by the furnace walls so that a greater weight of gases having a higher total heat content will be delivered from the furnace to the convection superheater and the transition section. This increase in gas weight is particularly effective in raising the proportion of the heat absorbed by the convection heating surfaces so as to adjust the proportion of heat absorbed in superheating to that absorbed in vaporization to the end that the location of the transition position will not shift widely, and particularly not back into the furnace, with the desired final degree of superheat being concurrently maintained.

The invention involves the use of flue gas recirculation in a once-through steam generator through either or both the hopper of the furnace or in the exit part of the furnace and this action takes place in such a controlled manner that not only the total amount of heat absorption by the evaporating wall surface of the furnace is reduced to a point where feed water temperatures of modern power plant practice can be satisfactorily utilized, but permitting a wide load range on the unit while still maintaining the transition zone in a cooled gas section of the steam generator, downstream gas flow-wise of the high temperature superheater. Low feed water temperatures to the boiler do not fit in with modern regenerative turbine heat cycles which obtain high thermal efficiency through the use of progressive regenerative heating of the feed water to relatively high temperatures.

The gas weight increase due to recirculation will result in a gas temperature leaving the economizer which will be slightly higher than the temperature which would occur for the same fuel input without the recirculation. While the increased gas flow entering at slightly lower temperature may not appreciably affect the amount of heat absorbed by the superheater, which is the first surface passed over, its effect on increased absorption becomes more pronounced as it passes down over the evaporative surface below the transition position and then over the economizer. A slight decrease in total heat absorption by the convection surfaces will occur due to the increased gas weight and also slightly higher gas exit temperature (or stack temperature). This alone would have an effect of moving the transition position downward towards the inlet header 58 and correspondingly increasing the extent of surface above the transition position which is superheating surface. Thus the superheat temperature might tend to be slightly deficient but it would be corrected by the controls regulating the fuel input. The controls, however, would also operate to bring this into proper balance following the regulation of the recirculation to the upper part of the furnace.

In the illustrative arrangement, the recirculated gases, which are introduced to prevent slagging temperatures, are introduced at a level intermediate the height of the furnace. Their introduction will undoubtedly affect the

absorption of the furnace wall tubes from that position up to the furnace outlet and this will have an offsetting effect as regards increased absorption in the convection pass, inasmuch as the total heat absorbed by the furnace is thereby reduced and such a reduction tends to shift the transition position upward from the inlet header 58.

The location of ports 172 at an intermediate position is a compromise measure for attaining mixing of the recirculated gases and products of combustion before they reach the superheater surface. An optimum position for introducing such recirculated gases would be directly at the furnace gas outlet if uniform mixing with the products of combustion coming directly from the burners could still be effected.

15 Although the invention has been described with reference to a specific unit, and its operation, it is to be appreciated that the invention is not limited to all of the details thereof, but is rather of a scope commensurate with the scope of the subjoined claims.

20 I claim:

1. In a once-through vapor generating and superheating unit having a primary section including a furnace with liquid heating tubes along its walls, furnace firing means, said tubes receiving heat radiantly transmitted from the furnace gases, a liquid to vapor transition section of the once-through type including tubes receiving heated liquid at their inlet ends and heated by the gases after they have left the furnace to complete the vaporization within a transition zone flow-wise ahead of the outlet ends of the tubes, means forming a gas pass leading from the furnace and having the transition section arranged therein to receive all of the gases exiting from the furnace, a recirculated gas system extracting furnace gases from a position downstream gas flow-wise of the transition section and introducing the recirculated gases into the gases in the furnace at a position affecting the heat absorption of a major portion of the length of said furnace wall tubes, and means operating to increase the flow of recirculated gases through said system when the transition zone tends to shift toward the furnace tubes and thereby preventing any substantial shifting of the transition zone in that direction.

2. In a once-through vapor generating and superheating unit having a radiation section including a furnace with liquid heating tubes along its walls, furnace firing means, said tubes receiving heat radiantly transmitted from the furnace gases, a liquid to superheated vapor transition connection section of the once-through type including long tubes receiving heated liquid at their inlet ends and convectionally heated by all of the gases from the furnace to complete the vaporization and initiate the superheating of the vapor within a transition zone flow-wise ahead of their outlet ends, a superheater receiving the superheated vapor from the tubes of the transition section and contacted by higher temperature furnace gases to further superheat the vapor, and means for maintaining the transition zone within the transition section including a recirculated gas system regulably withdrawing furnace gases from a position downstream gas flow-wise of the transition section and introducing the recirculated gases into the gases in the furnace partially at a position between the furnace firing means and the transition section and partially ahead of the furnace firing means in a gas flow sense.

3. In a method of operating a once-through vapor generating and superheating unit having a furnace with liquid heating tubes therein; means firing the furnace, and a convection section receiving gases from the furnace and including a once-through bank of series connected vapor generating and superheating tubes receiving the liquid heated by the furnace tubes and having a liquid to vapor transition zone therein; the method of maintaining the transition zone within said once-through tubes by regulating the division of the total available heat of the unit between the furnace tubes and the tubes of the con-

vection section by controllably recirculating gases from a point gas flow-wise beyond the furnace gas outlet to the furnace simultaneously to a first position between the furnace gas outlet and the firing means and to a second position upstream (gas flow-wise) of the furnace firing means, regulating the recirculated gas flow to the first position from indications of the gas outlet temperature of the furnace, said regulating including the increasing of recirculated gas flow as the gas outlet temperature tends to increase, and also regulating the recirculated gas flow to the second position from indications of superheated vapor temperature and vapor flow, said regulating of recirculated gas flow to the second position involving the changing of the flow inversely to the tendency of the vapor temperature to change.

4. In a method of operating a once-through vapor generating and superheating unit having a furnace with liquid heating tubes therein, means firing the furnace, and a convection section receiving gases from the furnace and including a convection vapor superheater having once-through liquid to vapor transition tubes receiving liquid from the outlets of the furnace tubes, the method of regulating the division of the total available heat of the unit between the furnace tubes and the tubes of the convection section by controllably recirculating furnace gases from an inlet point gas flow-wise beyond the furnace gas outlet to first and second positions within the furnace to stabilize the zone of liquid to vapor transition in the convection section, pumping vaporizable liquid into the unit in accord with indications of vapor pressure and from indications of vapor flow from the unit, increasing the pumping rate when the pressure or vapor flow falls below a predetermined value, controlling the rate of recirculated gas flow to said first position (between the firing means and the furnace gas outlet) from indications of gas temperature at the furnace outlet and from indications of vapor flow from the unit, controlling the rate of firing from indications of vapor flow and from indications of final superheated vapor temperature, of the firing rate involving an increase in the firing rate when the vapor flow or the final superheated vapor temperature falls below a predetermined value, and controlling the flow of recirculated furnace gases to the second position (upstream gas flow-wise of the firing means) from indications of intermediate superheated vapor temperature adjacent the transition zone and from indications of superheated vapor flow from the unit and indications of recirculated gas flow, the controlling of the rate of recirculated gas flow to said first position involving the increasing of gas flow as the gas temperature at the furnace outlet and the vapor flow tend to increase while the controlling of the recirculated gas flow at the second position involves increasing the gas flow as the intermediate superheated vapor temperature and the superheated vapor flow tend to decrease.

5. In a method of operating a vapor generating and superheating unit having a furnace with liquid heating tubes therein, means firing the furnace, and a convection section receiving gases from the furnace and including a convection vapor superheater, the method of regulating the division of the total available heat of the unit between the furnace tubes and the convection section by controllably recirculating furnace gases from an inlet point gas flow-wise beyond the furnace gas outlet to first and second positions within the furnace, controlling the rate of recirculated gas flow to said first position (between the firing means and the furnace gas outlet) from indications of gas temperature at the furnace outlet and from indications of vapor flow from the unit, controlling the rate of firing from indications of vapor flow and from indications of final superheated vapor temperature, the control of the firing rate involving an increase in the firing rate when the vapor flow or the final superheated vapor temperature falls below a predetermined value, and controlling the flow of recirculated furnace gases to the second position (upstream gas flow-wise of the firing

means) from indications of intermediate superheated vapor temperature and from indications of superheated vapor flow from the unit, the controlling of the rate of recirculated gas flow to said first position involving the increasing of gas flow as the gas temperature at the furnace outlet and the vapor flow tend to increase while the controlling of the recirculated gas flow at the second position involves increasing the gas flow as the intermediate superheated vapor temperature and the superheated vapor flow tend to decrease.

6. In a vapor generating and superheating unit having a furnace provided with a heating gas outlet, liquid heating tubes associated with a boundary wall of said furnace adjacent the point of fuel entry and arranged to receive heat mainly by radiation from the heating gases in the furnace, fuel burning means normally burning a fluid fuel in suspension in the furnace at such a location as to provide heat radiation from the main combustion zone to said furnace wall tubes, and a liquid to superheated vapor transition section including convection tubes arranged to receive heat from heating gases after they have left said gas outlet, each of said convection tubes receiving at one end liquid from the generating tubes and discharging superheated vapor at its other end, the method of controlling the liquid to superheated vapor transition zone and maintaining it in said transition section, which comprises withdrawing heating gases from a location in the heating gas flow downstream gas flow-wise of at least a part of said transition section and introducing the withdrawn gases into the furnace in varying amounts in counter relation to movements of the transition zone, the rate of introduction of the withdrawn gases being increased when the transition zone moves toward the combustion zone, said introduction of recirculated furnace gases being effected and controlled from indications of intermediate superheated vapor temperature adjacent the transition zone and from indications of superheated vapor flow, and introducing a controlled proportion of the withdrawn furnace gases into the furnace at a position adjacent the furnace gas outlet, said last introducing of furnace gases being controlled from indications of gas temperature at the furnace outlet and from indications of vapor flow from the unit, the first mentioned control of recirculated gas introduction including the increase of recirculated gas flow as the vapor flow and intermediate superheated vapor temperature decrease from an optimum value or values while the second mentioned control of recirculated gas introduction involves the increase of recirculated gas flow as gas temperature at the furnace outlet and rate of vapor flow tend to increase.

7. A forced flow once-through vapor generating and superheating unit comprising walls defining a furnace chamber having a heating gas outlet, means for firing said furnace chamber, vapor generating tubes lining the walls of said furnace chamber and arranged to absorb heat mainly by radiation from the furnace heating gases, means forming a convection heating gas pass arranged to receive all of the heating gases from said gas outlet, groups of tubes extending across said heating gas pass arranged to absorb heat mainly by convection from said heating gases and serially connected to said furnace wall tubes to form at least one once-through fluid passage arranged to receive a vaporizable liquid at one end and to discharge superheated vapor at the other end, pump means arranged to supply a vaporizable liquid to the inlet end of said fluid passage, said fluid passage including a transition point normally located closer to said other end and at which 100% of the liquid will be vaporized and which tends to move towards the liquid inlet end of said fluid passage with a decrease in load on said unit, and means for effecting a movement of said transition point away from said liquid inlet end on a decrease in load including a recirculated gas system arranged to withdraw heating gas from a point downstream of said convection heated tubes and to introduce the withdrawn gas into said furnace

chamber at a position affecting the heat absorption of a major portion of the length of said furnace wall tubes.

8. In a forced flow once-through vapor generating and superheating unit, the method of operation which comprises burning a fuel in a furnace chamber at a location remote from the heating gas outlet therefrom, absorbing heat from the furnace heating gases flowing to the gas outlet mainly by radiation to vapor generating surface lining the boundary walls of the furnace chamber, absorbing heat from all of the heating gases leaving said heating gas outlet mainly by convection to fluid heating surface serially connected to the furnace vapor generating surface and forming therewith at least one once-through fluid passage receiving a vaporizable liquid under pressure at one end and discharging superheated vapor at its other end and including a transition point in the convection heated heating surface at which 100% of the liquid will be in a vaporized condition and tending to move toward the liquid inlet end of said fluid passage with a decrease in load on said unit, and effecting a movement of said transition point away from the liquid inlet end of the fluid passage on a decrease in load by introducing a relatively low temperature gas into the furnace chamber at a position effecting a reduction in the radiant heat absorption of a major portion of the vapor generating surface lining the walls of the furnace chamber.

9. In a forced flow once-through vapor generating and superheating unit, the method of operation which comprises burning a fuel in a furnace chamber at a location remote from the heating gas outlet therefrom, absorbing heat from the furnace heating gases flowing to the gas outlet mainly by radiation to vapor generating surface lining the boundary walls of the furnace chamber,

absorbing heat from all of the heating gases leaving said heating gas outlet mainly by convection to fluid heating surface serially connected to the furnace vapor generating surface and forming therewith at least one once-through fluid passage receiving a vaporizable liquid under pressure at one end and discharging superheated vapor at its other end and including a transition point normally located closer to said other end and at which 100% of the liquid will be in a vaporized condition and tending to move toward the liquid inlet end of said fluid passage with a decrease in load on said unit, and effecting a movement of said transition point away from the liquid inlet end of the fluid passage on a decrease in load by withdrawing heating gas from a location downstream of said convection heated heating surface and introducing the withdrawn gas into the furnace chamber at a position effecting a reduction in the radiant heat absorption of a major portion of the vapor generating surface lining the walls of the furnace chamber.
